AIR PURIFIER

Joseph J. Rinaldi, Liverpool, N.Y., assignor to Aldon Industries Corporation, Syracuse, N.Y., a corporation of New York

Filed May 1, 1961, Ser. No. 64,975

Term of patent 3½ years

(Cl. D16—2)

The side not shown is a mirror image of the side shown in FIGURE 3, and the rear is substantially plain.

I claim:

The ornamental design for an air purifier, substantially as shown and described.
